GRADING MECHANISM FOR PATTERN-REPRODUCING MACHINES.

1,302,303.

Specification of Letters Patent. Patented Apr. 29, 1919.

Application filed September 7, 1915. Serial No. 49,415.

To all whom it may concern:

Be it known that I, FRANK S. BUCK, a citizen of the United States, and resident of Springfield, in the county of Windsor and State of Vermont, have invented certain new and useful Improvements in a Grading Mechanism for Pattern-Reproducing Machines, of which the following is a specification.

- 10 The present invention relates to a mechanism for grading in connection with machines or devices which cut, trace, or otherwise produce forms or figures like or geometrically similar to a pattern or model.
- 15 Among types of articles, in the production of which grading mechanisms embodying essentially the invention hereinafter described are used, may be named particularly forms or patterns for articles for personal
- 20 wear, or parts of such articles, or to be used in the manufacture of such articles, which are made with general similarity to one another but differing in size in one or more dimensions from one another. The different
- 25 sizes of such articles are commonly developed from a standard pattern or model and are "graded" up or down from such pattern, that is, are made larger or smaller than the pattern in one dimension or all dimensions in a given proportion to the pattern. It is essential that the form or outline of an article be developed from a standard pattern with larger or smaller dimensions strictly proportionate to the
- 30 dimensions of the standard pattern. The essentials of the invention may be used with any type of reproducing machine in which articles graded from the standard pattern or model are developed, including
- 35 machines for producing articles of three dimensions as well as those of which the contours are all in the same plane. Among other types of machines to which the invention may be applied may be named lathes
- 40 for turning irregular forms.

The object of the invention is to provide an improved and simple grading mechanism for the purpose indicated which will secure minute or large variations in grade with absolute accuracy. An important feature of the invention is a novel organization of model holding and following instrumentalities; work holding and reproducing instrumentalities, means for effecting relative

traverses between these instrumentalities 55 taken in pairs and mechanism for maintaining a constant velocity ratio between the traverses throughout the production of a piece of work. This organization insures rigorously accurate geometric reproduction 60 of the model.

Another feature is a novel mechanism connecting two carriages (and in the machine shown transmitting motion from one to the other), the mechanism having a member 65 to which a movement independent of the movement communicated to the carriages by the main drive can be imparted, the mechanism being constructed and arranged to transmit this movement multiplied by a constant, which may be unity, to one of the carriages. In the machine shown this movement has a uniform ratio to the movement imparted by the main drive, and the two carriages are thus given velocities differing 70 by the same amount during all parts of the production of a piece of work.

An important feature of the connecting mechanism is the rectilinear movement of the independently moving member. The 80 significance of this feature depends upon the fact that the velocity relations of rectilinearly moving parts are much simpler than those of cranks or links. The rectilinear moving part is, in the mechanism 85 shown, given a movement from a rectilinear guide disposed at an angle to the direction of drive so that a velocity strictly proportional to the velocity of drive is imparted to it. This velocity is transferred multiplied by a constant, which may be unity, 90 through the connecting mechanism and is algebraically added to the velocity imparted to a carriage by the main drive, so that the difference in velocity of the carriages is 95 always strictly in constant proportion to the velocity imparted by the main drive. If the main drive is at uniform velocity, the velocities of both carriages will be uniform, and their ratio constant. The specific mechanism shown transmits this incremental velocity through racks and pinions so that its amount is unchanged from one part of the mechanism to another, as well as at the end of the mechanism. An important feature 100 is a novel connecting mechanism between the carriages having a member constructed and arranged to be operated to alter the

effective length of the mechanism at a rate strictly proportional to the velocity of a carriage. In the machine shown, the member is moved transversely of the connecting mechanism independently of the movement of the mechanism of the main drive.

These and other features of the invention including certain details of construction and combinations of parts will appear more fully from the following description of a preferred embodiment of the invention shown in the accompanying drawings and will then be pointed out in the appended claims. The nature of the invention sufficiently appears from the following detailed description of one specific embodiment thereof adapted to lathes for turning irregular forms which I have illustrated in the accompanying drawings.

20 Figure 1 is a front elevation of such a lathe.

Fig. 2 is an end view of the lathe as seen from the left of Fig. 1.

Fig. 3 is a detail view of the grading mechanism, the same being a section taken on line 3-3 of Fig. 2, and Fig. 4 on an enlarged scale.

Fig. 4 is a horizontal section on line 4-4 of Fig. 3.

30 Fig. 5 is a vertical section on line 5-5 of Fig. 4.

Fig. 6 is a rear view of the lathe; and Fig. 7 is a section on the line 7—7 of Fig. 6.

The same reference characters indicate
35 the same parts in all the figures.

After first explaining that the illustration of my invention in connection with a machine for turning irregular forms is not intended, and is not to be considered, as a limitation of the invention to machines of that type, but is merely presented to illustrate a practical and useful embodiment or adaptation of the invention, I will proceed to a detailed description of this particular embodiment.

In the drawings, 10 represents a carrier which is adapted to slide on ways or guides, one of which is shown at 11 on the frame of the machine. This carrier supports standards 12 having bearings in which is mounted a shaft 13 carrying a cutter head 14 equipped with cutters 15. The cutter head and cutters represent one type of instrument for reproducing the form of the model or pattern, and may be considered as typical of any instrument for this purpose, whether the same is used to cut a surface of revolution or an outline, or merely to trace or mark an outline on a plane surface without cutting. The carrier 10 is constrained by the guideways 11 to travel in a fixed path. Another standard or upright 16 on the carrier 10 is equipped with guideways 17 and supports a second carrier 18, which is engaged with said guideways 17.

The second carrier is movable upon the first carrier in the direction limited by the ways 17, which are parallel to the ways 11 on which the first carrier travels. That is, the second carrier is supported and moved by 70 the first carrier and is also movable relatively thereto in the same direction or the opposite direction. The second carrier carries a follower 19, which in this machine is a wheel adapted to bear on the surface of 75 the pattern or model, such pattern or model being supported by centers 20, 21 on a frame 22, which is movable in and out with respect to the line of travel of the carriers. The frame 22 is pivotally mounted at 50 on 80 horizontal links 52 the ends of which are pivoted at 54, 56 to the lower and upper ends, respectively, of parallel swinging links 58, 60, pivoted to the main frame at their other ends. The forward side of the frame 85 rolls on circular segments 62, pivoted at their centers 64. A substantially horizontal movement is thus given the frame by the pressure against the model wheel 19 and a counterweight hung over the pulley 90 66, as is well understood. This and other swing frame mechanisms are well known in the art and no further description is thought necessary. Said frame 22 also has centers 23, 24 for supporting the work piece 95 out of which the form is cut by the reproducer. The centers 20 and 23 are rotated in unison by mechanism common in machines of this character, or any other suitable mechanism, the precise nature of 100 which is not at all material to this invention. The cutter is also rotated about the axis of the shaft 13, by means of a belt 25 passing around a driving drum 26 and over a pulley 27 on the shaft 13. The rotation of 105 this particular type of cutter is necessary in order that it may accomplish its purpose, but as rotation of the cutter is not necessary in all types of reproducing machine, and moreover as it is not novel in the particular 110 type of machine here illustrated, I do not assert this feature as an essential part of the invention.

In the rear of the machine is a guide bar 28 pivotally mounted at one end on pivot 29 115 on a fixed frame member 29' so that the opposite end 30 may be raised and lowered, in a vertical plane, parallel to the paths in which the carriers travel, whereby the bar may be inclined up or down with respect 120 to these paths. The clamp 30' secures the end 30 in adjusted position to a fixed frame member 30. A slide or traveler 31 is mounted on the guide bar 28 and is adapted to travel thereon. Said traveler is connected 125 by a swivel coupling with a stud 32, which projects from a rack bar 33 arranged to travel vertically in a guide 34, which is formed upon a bracket 35 having flanges 36 whereby the bracket is secured to the rear 130

- side of the upright 16 on the cutter carriage. A retaining strip or bar 37 is secured to one side of the guideway to bear against an adjacent side of the rack bar, and a second retainer 38 is secured to the edge of the guideway to overlie the outer or rear side of the rack bar. These retainers prevent removal of the rack bar from the guideway, except in endwise direction, and limit its travel to a path extending longitudinally of the length of the guideway, which in the present machine, is vertical. Said rack may be considered to be the actuator of the mechanism hereinafter described.
- 15 The bracket 35 is provided with a bearing 39 in which is rotatably mounted a shaft 40 having fixed upon its ends gear wheels 41 and 42, respectively, said gears abutting against the ends of the bearing and thereby holding the shaft against end shake. The teeth 43 of the rack bar mesh with the teeth of the gear wheel 41. The second wheel 42 meshes with a horizontal rack 44 which is secured to the under side of a ledge 45 projecting rearwardly from the base of the second carrier 18 and overlying the gear 42. The rack 44 is longitudinally adjustable on the carrier 18 by means of the screw 46.
- 20 The foregoing describes all that is material to my present invention. The other elements and mechanisms shown in the drawings are parts which, although necessary to the practical operation of the particular machine here illustrated, have no immediate connection with the particular mechanism in which my present invention is embodied, and therefore do not affect the present invention. For this reason I have not attempted to describe such parts and mechanisms.
- 25 The operation of the grading mechanism will be readily understood and is as follows. Of course when the carrier 10 with its upright 16 is moved, from right to left by the main drive, as is usual in machines of this type the carrier 18 is moved with it, and the rate of movement of the second carrier is greater or less than the first according to the inclination given to the bar 28. If this bar be inclined downward in the direction of movement of the carrier, when this direction is from right to left, (Fig. 1) the traveler or slide 31 is gradually lowered, thereby lowering the rack bar 33, rotating the gear wheels 41 and 42, and advancing the rack 44, horizontally relative to the gear wheels. This movement of the rack 44 is algebraically added to the movement 30 transmitted to the carrier 18 through the mechanism 33, 41, 42, 44 from the carrier 10 thus moving the second carrier 18 faster than the first carrier. The degree of slant or angle of inclination of the bar 28 of course determines the increment in velocity of the carrier 18. Adjustments of this character, that is with a downward inclination of the guide bar, from right to left as seen in Fig. 1, are employed in grading down, that is in producing work smaller than the model. 70 When the guide bar is upwardly inclined with respect to the direction of travel of the carrier from right to left, the rack bar 33 is raised and a movement thereby given to the rack and carrier 18 relatively to the 75 carrier 10 in the direction opposite to the movement of the latter, but at a rate less rapid than the movement of the carrier 10, whereby the resulting effect is to cause the carrier 18 to travel in the same direction 80 with the carrier 10 but at a slower speed. In this way work pieces longer than the model but similar thereto may be produced. When the guide bar is horizontal, that is, exactly parallel to the path of the carrier, 85 no movement is given to the rack 33 or to the carrier 18 relatively to the carrier 10, but the carriers are both moved at the same speed. The effects are exactly the reverse of those above described when the direction 90 of carrier travel is from left to right; and also when the rack 33 is placed at the right hand side of the gear 41, instead of at the left of this gear, or the rack 44 is below the gear 42 instead of above it. Accordingly I 95 do not intend the foregoing description of operation to be taken as in any sense a limitation of the invention to a machine in which the working travel of the carriers is from right to left, or to exclude from the 100 scope of my claimed protection any apparatus in which the direction of such travel is the reverse of this, or in which the relative positions of either of the racks and pinions or equivalent elements, are reversed. 105
- It will be apparent that the mechanism 33, 41, 42, 44 connects the two carriages and transforms the velocity of one into the velocity of the other by transmitting this velocity from the one to the other and by algebraically adding to it a definite arbitrary percentage of itself, constant throughout the production of a piece of work. The vertical velocity imparted to the rack 33 is strictly proportional to that of the carrier 10, being 110 equal to the velocity of the carrier 10 multiplied by the tangent of the angle of inclination of the guide bar 28. This velocity is transferred unchanged into the periphery of the pinion 41 and then appears in the 115 periphery of the pinion 42 multiplied by the ratio of the diameters of the two pinions (which need not be of the same diameter). The resulting velocity is then transferred 120 unchanged into the rack 44. All the velocities mentioned are taken relative to the carrier 10, and all are strictly proportional to the velocity of the carrier 10. It is not at all necessary to the fundamental idea of the invention that the secondary carrier be 125 130

mounted on the primary carrier, for this mode of mounting is merely a peculiar feature of the particular machine chosen for illustration of one form of the invention; 5 but on the contrary the two carriers may be located in any other relation to each other. The rack and pinion gearing between the two carriers is equally effective to transmit motion from the primary to the secondary 10 carrier at the same speed or with a positive or negative increment, whether the secondary carrier is supported independently of the primary carrier, or upon the latter. Neither is it essential that the guide bar be arranged for adjustment angularly in a 15 vertical plane rather than in a horizontal, or any other, plane; or that the rack 33 be located and movable vertically, rather than horizontally or at an inclination. Any other 20 arrangement of the guide and rack than that shown may be adopted provided the guide is adapted to be set to converge toward or diverge from the direction of travel of the primary carrier, and the rack 43 is adapted 25 to move transversely of such direction.

The essential elements of the last lathe are the model holder and the model follower; and the work holder and the reproducer or cutter, and some means for producing relative traverses between members of each 30 pair of these instrumentalities. The gist of my invention is the production of a constant velocity ratio between these traverses during the production of a piece of work. 35 Last lathes in use prior to the present invention have produced only an approximation to this constant velocity ratio. They have all made use of swinging arms and eccentric connecting rods which make it impossible to maintain constancy of velocity 40 ratio between the traverses, and make it impossible to maintain even an approximate constancy of velocity ratio in grading very far from the model. Shoe manufacturers are 45 insisting upon more and more rigid accuracy in the lasts they buy, and defects which are utterly inappreciable to the ordinary observer will condemn a last utterly. A constant velocity ratio between the traverses 50 insures the production of work which is geometrically similar to the model in the graded dimension.

In the claims I have used the term "model 55 instrumentality" as generic to the model wheel or follower and the model holding mechanism; and have similarly used the term "work instrumentality" as generic to the cutter or reproducer and the work holding mechanism. The carriers may each 60 carry one member from either pair.

The term "reproducer" is intended to include the cutter head herein described and also any other sort of device for reproducing a pattern or model whether by cutting 65 the outlines or form thereof or by

merely indicating such outlines or form without cutting the same. The model guide wheel 19 here illustrated is to be considered as typical of any sort of guide adapted to bear against a model or pattern and determine the relation of the work to the reproducer. 70

What I claim and desire to secure by Letters Patent is:

1. A pattern grading apparatus comprising essentially a primary carrier, a secondary carrier, a model instrumentality mounted upon one of said carriers and a work instrumentality mounted on the other carrier, and a motion adding mechanism comprising a stationary guide bar adapted to be placed at an inclination to the directions in which said carriers travel, a slide engaged with said bar and carried by the primary carrier and toothed gearing for converting the displacements of said slide into uniform increments of movement of the secondary carrier. 75 80 85

2. A pattern grading apparatus comprising essentially a primary carrier, a secondary carrier, a model instrumentality mounted upon one of said carriers and a work instrumentality mounted on the other carrier, the secondary carrier being also engaged with the primary carrier whereby to be 90 moved therewith, a motion adding mechanism comprising a guide bar adjustable in a plane parallel to the line of movement of said carriers and adapted to be placed at a variety of inclinations to such line of movement, a rack bar carried by the primary carrier and guided thereby with provision for moving transversely to the path of movement of the carrier, a slide connected to said rack and engaged with said guide bar, a second rack connected to the secondary carrier and extending in the direction of movement of the latter, and gearing meshing with the two racks for transmitting movement from one to the other. 95 100 105 110

3. A pattern grading apparatus comprising essentially a primary carrier, a secondary carrier, a model instrumentality mounted upon one of said carriers and a work instrumentality mounted on the other carrier, the secondary carrier being also engaged with the primary carrier whereby to be moved therewith, a motion adding mechanism comprising a toothed gear train mounted upon the primary carrier and arranged to apply force to the secondary carrier in the direction of movement thereof, a guide which is fixed relatively to the carriers, and an actuating member engaged with said guide and arranged to drive said gear train. 115 120 125

4. A grading mechanism comprising primary and secondary carriers, one of which is guided to move in a fixed path, and the other of which is movable relatively thereto in the same directions, and a velocity trans- 130

forming mechanism comprising a fixed guide inclined to the paths in which said carriers move, an actuator slideable along said guide and adapted to be moved thereon by movement of the carriers, being at the same time displaced by the guide transversely to the path of the carriers, and mechanism operated by said actuator for converting the transverse displacement of 10 the latter into uniformly increased or diminished movement of one of the carriers relatively to the other.

5. A grading apparatus comprising a primary carrier guided to move in a fixed path, 15 a secondary carrier guided to move relatively to the primary carrier in approximately the same directions, motion transmitting rack and pinion gearing mounted on the primary carrier and engaged with the 20 secondary carrier for imparting movement to the latter relatively to the primary carrier, an actuator for the said mechanism, and an adjustable guide stationary relatively to the carrier with which said actuator 25 is engaged, said guide being adapted to impart movement to the actuator transverse to the paths in which the carriers travel.

6. A pattern grading mechanism comprising a carrier for a model instrumentality, a 30 carrier for a work instrumentality, both of said carriers being movable and one of them being movable relatively to the other, a rack mounted upon one of said carriers extending in the direction of the relative movement between the carriers, a gear mounted upon the other carrier and meshing with said rack, a second rack geared to actuate the said gear wheel and being movable transversely to the paths in which the carriers 35 move, an actuator for the second rack attached thereto and means operable by movement of the carrier for shifting said actuator transversely to said path of movement.

45 7. A grading mechanism comprising two relatively movable carriers, one being adapted to carry a model instrumentality and the other to carry a work instrumentality, complementary intermeshing gear elements 50 mounted upon said carriers, respectively, one of said elements being a driving element, an actuator for the said driving element and means operable by movement of the carrier on which said driving element is mounted 55 for simultaneously moving said element relatively to said carrier.

8. A grading apparatus comprising a model guide carrier, a pattern reproducer carrier, said carriers being guided to move 60 in parallel paths and one of them being thus movable relatively to the other, a rack secured to one of said carriers, a gear wheel mounted rotatably on the other carrier and meshing with said rack, and actuating means 65 for rotating said wheel when the carrier

mounting said wheel is moved, whereby a uniformly increased movement is transmitted from this carrier to the other carrier.

9. A grading mechanism comprising a traveling carrier guided to move in a fixed path, a second carrier guided movably in a path parallel to that of the first carrier, a rack secured to the second carrier extending in the direction in which the latter travels, a gear wheel mounted rotatably on the first 70 carrier meshing with said rack, a second gear wheel rigidly secured to the first gear wheel, a rack meshing with the second gear wheel and guided to move transversely to the movement of the two carriers, a slide 75 connected to the second rack and a guide bar engaged with said slide and adapted to be placed at an inclination to the paths of movement of the carriers.

10. In a lathe for turning irregular forms, 80 a carrier guided to travel in a horizontal path, a work instrumentality on said carrier, a second carrier movable in a definite path parallel to that of the first carrier, a model instrumentality on the second carrier, a rack 85 secured to the second carrier parallel to the path of movement thereof, a pair of rigidly coupled gear wheels rotatably mounted on the first carrier; one of said gear wheels being in mesh with said rack, a second rack 90 meshing with the other gear wheel of said pair, a guide secured to the first carrier holding the second rack and constructed to limit the movement thereof to a line transverse to the path of movement of the carriers, a guide bar angularly adjustable in a plane parallel to the path of movement of the first slide, whereby it may be placed at various inclinations to such path, and a slide 95 engaged with said guide bar and connected 100 with the second rack.

11. A lathe for turning irregular forms comprising, in combination with means for holding and means for rotating a work piece and a model, a movable cutter carriage, a 110 follower carriage mounted on the cutter carriage and movable relatively thereto, rigidly connected gear wheels rotatably mounted on one of said carriages, a rack in mesh with one of said wheels carried by said carriage 115 and guided to travel in directions transverse to the travel of the carriage, a second rack fixed to the other carriage and meshing with the other of said gear wheels, a stationary guide bar adjustable to extend at an inclination to the travel of the carriages, and a slide engaged with said guide bar and connected to the first named rack.

12. The combination with a plurality of carriages movable absolutely and also relatively to one another in the same and in opposite directions, of transmission mechanism adapted to impart uniform increments or decrements of motion from one carriage to the other, comprising two pinions rigidly 125 130

- connected together carried rotatably by one of the carriages, a rack guided on the same carriage to move transversely to the line of travel thereof, a relatively fixed guide, 5 means connected with said rack engaging said guide for shifting the rack when the carriage is moved, and a rack secured to the other carriage meshing with the second pinion.
- 10 13. In a machine of the class described, model holding and model following instrumentalities; work holding and reproducing instrumentalities; two carriages, each carrying one instrumentality of each pair, and 15 means for moving the carriages to effect relative traverses between these instrumentalities taken in pairs, comprising mechanism constructed and arranged to maintain a constant velocity ratio of arbitrary magnitude 20 between the said traverses throughout the production of a piece of work, said mechanism comprising a member having, when the said ratio is different from unity, a movement proportional to the said ratio and 25 transverse to the movement of the member when the said ratio is unity.
14. In a machine of the class described, model holding and model following instrumentalities; work holding and reproducing instrumentalities; two carriages, each carrying one instrumentality of each pair, means for moving the carriages to effect relative traverses between these instrumentalities taken in pairs, comprising a train of 30 mechanism having its terminal members connected with the two carriages respectively, and means for giving a terminal member a movement independent of the movement of the carriage with which it is connected, the 35 train being constructed and arranged to transmit the independent movement, unchanged in amount, from one terminal member of the train to the other.
15. In a machine of the class described, 40 model holding and model following instrumentalities; work holding and reproducing instrumentalities; two carriages, each carrying one instrumentality of each pair, means for moving the carriages to effect relative 45 traverses between these instrumentalities taken in pairs, comprising a train of mechanism connecting the carriages, and means for giving a member of the train a movement independent of the movement imparted to the 50 carriages by the said means, the train being constructed and arranged to transmit this independent movement, unchanged in amount, to one of the carriages.
16. In a machine of the class described, 55 model holding and model following instrumentalities; work holding and reproducing instrumentalities; two carriages, each carrying one instrumentality of each pair, means for moving the carriages to effect relative 60 traverses between these instrumentalities taken in pairs, comprising a train of mechanism having its terminal members connected with the two carriages respectively, and means for giving one terminal member a velocity having a desired ratio to the velocity of one of the relative traverses which is constant throughout the production of a piece of work, the train being constructed and arranged to transmit the former velocity from one terminal member of the train 65 to the other.
17. In a machine of the class described, model holding and model following instrumentalities; work holding and reproducing instrumentalities; two carriages, each carrying one instrumentality of each pair, and means for moving the carriages to effect relative traverses between these instrumentalities taken in pairs, comprising a train of mechanism connecting the carriages, and 70 constructed and arranged to transmit a velocity from one to the other which is proportional to the velocity of one of the said relative traverses throughout the production of a piece of work, the train comprising a member having, when the factor of the said proportionality is different from unity, a movement proportional to the said factor and independent of the movement made by the member when the said factor is 75 unity.
18. In a machine of the class described, model holding and model following instrumentalities; work holding and reproducing instrumentalities; two carriages, each carrying one instrumentality of each pair, means for moving the carriages to effect relative traverses between these instrumentalities taken in pairs, comprising a connection between the carriages constructed and arranged to transmit the movement of one to the other, and means for operating the connection to add algebraically to such transmitted movement a constant proportion of itself during the production of a piece of 80 work.
19. In a machine of the class described, model holding and model following instrumentalities; work holding and reproducing instrumentalities; two carriages, each carrying one instrumentality of each pair, means for moving the carriages to effect relative traverses between these instrumentalities taken in pairs, comprising a train of mechanism connecting the carriages constructed and arranged to transmit the movement of one carriage to the other, and means for imparting independent movement to a member of said train, the train being constructed and arranged to transmit this movement also, unchanged in amount, to the other carriage.
20. In a machine of the class described, model holding and model following instrumentalities; work holding and reproducing 85

instrumentalities; two carriages, each carrying one instrumentality of each pair, means for moving the carriages to effect relative traverses between these instrumentalities taken in pairs, comprising a train of mechanism connecting the carriages, and means for imparting independent movement to a member of the train proportional to the movement imparted to the system by the first said means, the train being constructed and arranged to transmit this movement, unchanged in amount, to one of the carriages.

21. In a machine of the class described, model holding and model following instrumentalities; work holding and reproducing instrumentalities; two carriages each carrying one instrumentality of each pair, means for moving the carriages to effect relative traverses between these instrumentalities taken in pairs, comprising a train of mechanism connecting the carriages, means for imparting independent movement to a member of the train proportional to the movement imparted to the system by the first said means, the train being constructed and arranged to transmit a constant proportion of this movement to one of the carriages during the production of a piece of work.

22. In a machine of the class described, model holding and model following instrumentalities; work holding and reproducing instrumentalities; two carriages, each carrying one instrumentality of each pair, and means for moving the carriages to effect relative traverses between these instrumentalities taken in pairs, comprising a connecting mechanism between the carriages, having a member constructed and arranged for movement independent of the movement communicated to the carriages by the said means, to alter the effective length of the connecting mechanism at a rate proportional to the movement communicated to the carriages by the said means.

23. In a machine of the class described, model holding and model following instrumentalities; work holding and reproducing instrumentalities; two carriages, each carrying one instrumentality of each pair, and means for moving the carriages to effect relative traverses between these instrumentalities taken in pairs, comprising a connecting mechanism between the carriages having a member constructed and arranged for movement transverse to the line of action of the mechanism to alter the effective length of the mechanism.

24. In a machine of the class described, model holding and model following instrumentalities; work holding and reproducing instrumentalities; two carriages, each carrying one instrumentality of each pair, and means for moving the carriages to effect relative traverses between these instrumen-

talities taken in pairs, comprising a connecting mechanism between the carriages having a member constructed and arranged for movement transverse to the line of action of the mechanism to alter the effective length of the mechanism at a rate proportional to the movement communicated to the carriages by the said means. 70

25. In a machine of the class described, model holding and model following instrumentalities; work holding and reproducing instrumentalities; two carriages, each carrying one instrumentality of each pair, means for moving the carriages to effect relative traverses between these instrumentalities taken in pairs, comprising a connecting mechanism between the carriages having a member constructed and arranged for movement transverse to the line of action of the mechanism to alter the effective length of the mechanism, and means for imparting to the member a velocity proportional to the velocity of one of the said relative traverses. 75

26. In a machine of the class described, model holding and model following instrumentalities; work holding and reproducing instrumentalities; two carriages, each carrying one instrumentality of each pair, and means for moving the carriages to effect relative traverses between these instrumentalities taken in pairs, comprising a connecting mechanism between the carriages, having a member constructed and arranged for rectilinear movement independent of the movement communicated to the carriages by the said means, to alter the effective length of the connecting mechanism at a rate proportional to the movement communicated to the carriages by the said means. 90 95

27. In a machine of the class described, model holding and model following instrumentalities; work holding and reproducing instrumentalities; two carriages, each carrying one instrumentality of each pair, and means for moving the carriages to effect relative traverses between these instrumentalities taken in pairs, comprising a connecting mechanism between the carriages having a member constructed and arranged for rectilinear movement relative to the line of action of the mechanism to alter the effective length of the mechanism. 100 105

28. In a machine of the class described, model holding and model following instrumentalities; work holding and reproducing instrumentalities; two carriages, each carrying one instrumentality of each pair, and means for moving the carriages to effect relative traverses between these instrumentalities taken in pairs, comprising a connecting mechanism between the carriages having a member constructed and arranged for rectilinear movement transverse to the line of action of the mechanism to alter the ef- 110 115 120 125 130

fective length of the mechanism at a rate proportional to the movement communicated to the carriages by the said means.

29. In a machine of the class described, 5 model holding and model following instrumentalities; work holding and reproducing instrumentalities; two carriages, each carrying one instrumentality of each pair, means for moving the carriages to effect relative 10 traverses between these instrumentalities taken in pairs, comprising a connecting

mechanism between the carriages having a member constructed and arranged for rectilinear movement transverse to the line of action of the mechanism to alter the effective 15 length of the mechanism, and means for imparting to the member a velocity proportional to the velocity of one of the said relative traverses.

In testimony whereof I have affixed my signature.

FRANK S. BUCK.
